UNITED STATES PATENT OFFICE.

DANIEL B. MEDANICH, OF BUECHEL, KENTUCKY, ASSIGNOR TO HIMSELF, PENDLETON J. B. PARENTEAU, JOHN R. WRIGHT, AND OLIVER H. KELSALL, OF LOUISVILLE, KENTUCKY, A PARTNERSHIP.

INTERNAL-COMBUSTION MOTOR.

1,227,169.

Specification of Letters Patent. Patented May 22, 1917.

Application filed July 13, 1914. Serial No. 850,584.

To all whom it may concern:

Be it known that I, DANIEL B. MEDANICH, a citizen of the United States, and resident of Buechel, county of Jefferson, and State 5 of Kentucky, have invented certain new and useful Improvements in Internal-Combustion Motors, of which the following is a specification.

The object of my invention is to improve 10 and simplify the valve mechanism and produce an efficient device positively operated at all times, without the use of springs and hence adapted to increase the efficiency of the motor and render the operation of the 15 valves practically noiseless. This I have accomplished by providing superimposed valve plates each provided with slots or openings corresponding with the intake and exhaust ports of the cylinder and adapted 20 by the reciprocation of the plates to open and close said ports periodically in accordance with the usual practice in four cycle type of combustion motors. My arrangement of the valve plates not only eliminates 25 noise but the plates present an extent of surface that reduces wear and the possibility of leakage to a minimum. Furthermore my construction renders it possible to compensate for any wear of the valve 30 plates, and to surround the valve plates by water so that during operation they are kept cool thus avoiding any burning of the valve openings.

Preferably I have shown my invention 35 in connection with a four cycle type of motor although it will be understood that it may be used in other types for which it is found adaptable.

With the foregoing, and other, objects in 40 view the invention consists of the novel construction illustrated in the accompanying drawings which form a part of this specification, in which is set forth an embodiment of the invention, but it is to be understood that such changes and variations may 45 be resorted to as come within the scope of the claim appended hereunto.

In the drawing, in which like reference 50 numerals indicate like parts in the several views; Figure 1, is a front elevation; Fig. 2, a vertical section, with parts in elevation, with the motor on the exhaust stroke; Fig. 3, a plan view; Fig. 4, a transverse section on line $x-x$ of Fig. 2; Fig. 5, a

side elevation with the cover of the valve chamber removed, and part of the crank-chamber wall broken away; Fig. 6, an elevation of the inner slide valve; Fig. 7, an elevation of the outer slide valve; Fig. 8, a development of the valve movement for 60 the four cycle stroke.

In the drawings, —1— designates the crank-chamber in which a crank-shaft —2— is adapted to rotate. —3— designates the cylinder in which a piston —4— is 65 adapted to reciprocate. The piston is connected to a crank —5— by a connecting rod —6— in the usual manner. The cylinder is made double, or provided with a surrounding space —7— forming a water 70 jacket in order to permit circulation of water about the cylinder and valves. One side of the cylinder is extended and provided with a vertical recess —9— which in conjunction with a cover —12— secured 75 on the cylinder at —13—, forms a valve chamber. The cover 12 has a space —14— forming a water jacket which communicates with the space 7. A vertical rib, or partition —15— separates the upper portion of the valve chamber into two parts, or sections. The cylinder is provided with two radially extending openings, or ports —18, 19— of which one, 18, is the inlet port for the entrance of gas to the cylinder, 80 and the other, 19, the exhaust port for the escape of the burned gases after the explosion. These ports are adapted 85 to register with corresponding openings through the cover 12 which are connected 90 in the usual manner with supply and exhaust pipes. Two superimposed plates, or valve members —10, 11— are loosely 95 mounted in the chamber 9 and adapted for reciprocation therein, these plates are each provided with a vertical slot —10a, 11a— adapted to embrace the rib 15. Each valve member, or plate 10 and 11 is provided 100 with two or more openings located in such position in the length of the respective plate that they may serve to open and close the ports 18 and 19 at the proper time during the four strokes as hereinafter more fully described. Openings —20, 21— in the valve slides are arranged to be brought 105 into register with each other and with the inlet port 18 to open said port for the admission of the explosive mixture, and open-

ings —22, 23— are adapted to be brought into register to open the exhaust port at the desired time to permit the escape of the burned gases after explosion. It will be observed that from the arrangement of the two sets of openings 20, 21 and 22, 23, that when the inlet port is fully open the openings 22 and 23 will be out of register and the exhaust port will be closed, and that when the openings 22 and 23 are in register with each other and with the exhaust port 19, thus opening the exhaust port, the openings 20 and 21 will be out of register and the inlet port closed. The valve members may be reciprocated in any suitable manner to obtain the desired result, but I have here shown the respective members as connected by means of connecting rods —24, 25— to cranks —26, 27— on a shaft —28— mounted in the crank case parallel with the crank shaft 5 and adapted to be driven therefrom. Any suitable means may be employed to drive the valve shaft from the crank shaft so long as the proper relation between the rotation of the crank shaft and the proper opening and closing of the inlet and exhaust ports is observed. As illustrated a sprocket wheel —29— is secured on the valve shaft and a sprocket —30— secured on the crank shaft 2, a sprocket chain —31— forming the driving connection between them, the relation between the sprockets 29 and 30 is such that it requires two complete revolutions of the crank shaft 2 for one of the valve shaft 28. The cranks on the valve shaft are set at an angle of approximately 90 degrees to each other, so that the valve slides 10 and 11 follow each other at a distance practically equal to one fourth of a revolution of the shaft 28. In Fig. 8, is shown a development of the motions of the slide valves during the four stroke cycle. The openings 20 and 21 in the two slide valves corresponding to the intake port being represented by the upper line of small rectangles, while the openings 22 and 23, in said slides, for the exhaust port are represented by the lower line of rectangles. The position of the inlet and exhaust ports 18 and 19 is indicated by the parallel lines extending horizontally across the lines of rectangles representing the valve openings in the slides. Studying this figure the various movements of the valve slides during the four strokes can be readily traced. Assuming the position of the piston 4 to be at the upper end of its stroke, ready to descend, with the intake valve just beginning to open, this point being indicated by the rectangles at the left end of the lower line of development. Following the development from left to right, it will be seen that the small rectangles, from step to step, are brought to overlap more and

more in the field of or between the lines representing the inlet port 18, and hence the inlet valve continues to open wider as the piston moves down, and then the openings 20 and 21 move apart so as to close the inlet port shortly after passing the line marked B, at which point the piston has reached the lower end of its stroke, and compression of the gases drawn into the cylinder will begin, as the piston rises. During compression it will be seen that the inlet valve openings in the slides move still farther out of alignment with the inlet port until the piston has returned to its uppermost position, completing the compression stroke, after which the explosion takes place, this point being indicated by the line C in Fig. 8. Continuing to trace the movement of the inlet openings through the explosion and exhaust strokes, it will be seen that the openings 20 and 21 are gradually brought back to the position in which the inlet valve begins to open for a repetition of the cycle, this position being indicated on the line E which corresponds with the position of the valve openings on the line A at the left end of the figure. Similarly tracing the movements of the valve opening with relation to the exhaust port, it will be seen from a study of the upper development in Fig. 8 that the exhaust port begins to open toward the end of the explosion stroke or just after the beginning of the up stroke of the piston on the exhaust stroke, the beginning of which is indicated on the line D. Further tracing of the opening of the exhaust port from the line D will show that it is brought to full opening and then gradually closed, complete closure however not taking place until after the inlet port begins to open for the next stroke as will be seen by the position of the rectangles at the left end of the lower line of development. It will thus be seen that during the operation of the motor, the exhaust port will be closed during the intake stroke, while the inlet port is open and gases are being drawn into the cylinder. During the compression stroke or during the first up stroke of the piston as the gases are compressed, both inlet and exhaust ports will be closed and will remain closed during the explosion stroke, after which the exhaust port will begin to open and will be fully opened during the up stroke of the piston when the burned gases will be forced out after which the cycle will again be repeated.

It is thought that the manifold advantages of my invention, and its construction and operation will be thoroughly understood from the foregoing without more extended description and, I claim;

In an internal combustion motor, the combination of a cylinder having exhaust

and inlet ports located side by side, a valve casing covering said ports, a pair of valves in the form of bifurcated super-imposed plates operable in said casing, a septum 5 dividing said casing and entering the bifurcation in said valves, each of said plates having an opening in each branch thereof, the openings in one plate being in lateral alinement, while those in the other plate are

not in lateral alinement, and means for reciprocating said valves to aline the respective openings therethrough with each other and with the exhaust and intake ports. 10
